UNITED STATES PATENT OFFICE

WILLIAM S. TIMBLIN, OF RIVER FOREST, ILLINOIS

UMBRELLA

Application filed November 28, 1927. Serial No. 236,053.

This invention relates to new and useful improvements in umbrellas more particularly to that type suitable for manufacture and sale at a low price for emergency purposes. 5 This invention has for one of its objects the provision of an improved emergency umbrella which may be manufactured at a low cost, is compact when folded and takes a preferably substantially rectangular form when 10 folded. Such an article may be readily deposited in a coin-operated dispensing machine ready for delivery therefrom as required, the article being in such form that it may be quickly and readily opened for use as desired. 15

Other objects of this invention reside in the provision of an improved umbrella formed of a substantially rectangular sheet of material having integral reinforcing portions forming the ribs; the provision of an 20 improved umbrella including a top portion and integrally formed reinforcing ribs, said ribs being so formed as to facilitate opening and closing of the umbrella, and affording a 25 substantially rectangular structure when folded; and an improved umbrella of the character referred to incorporating therein an improved handle construction which serves to extend the umbrella for use and also to retain the same in such spread or extended position. 30

This invention also contemplates an improved method of cutting and assembling flexible materials for the purpose of forming 35 the umbrella whereby the manufacture of the article is facilitated.

For the purpose of making clear to those skilled in the art the improvements in the 40 present invention, reference may be had in this connection to the subject matter of my co-pending application Serial No. 163,667, the invention of the present application being, in some respects, an alternative or modified form 45 of the same.

The foregoing and such other objects and advantages as may appear or be pointed out as this description proceeds are attained in the structure shown in the drawings in which:

50 Figure 1 is a bottom plan view of an um-

rella including the improvements of this invention.

Figure 2 is a transverse sectional view taken on the line 2—2 of Figure 1 looking in the direction indicated by the arrows. 55

Figure 3 is an elevational view from one edge illustrating the umbrella in position to be opened.

Figure 4 is a plan view of the same.

Figure 5 is a plan view of a sheet of material from which the umbrella is formed. 60

Figure 6 is a perspective view illustrating one method of assembling the parts of the umbrella.

Figure 7 is a perspective view of the article 65 closed or folded.

Figure 8 is a sectional view taken on the line 8—8 of Figure 1 looking in the direction indicated by the arrows.

Figure 9 is an enlarged fragmentary section 70 view of the handle pivot construction.

Referring now more particularly to the drawings, reference first may be had to Figures 1 and 2 which show the umbrella extended for use, and it will be observed that 75 the article includes a folding top portion 5 defined by a plurality of flexible sections 6, 6, these sections being joined together by the provision of radial ribs or reinforcing portions 7, 7. 80

The reinforcing portions 7 extend to the center of the top, as at 8, and are "gathered" at this point by adhesively connected portions and by the operation of the handle members 9 and 10 as will hereinafter appear 85 in detail.

It will be observed from an inspection of Figures 1 and 7 that the reinforcing ribs are divided substantially into two groups by the construction, as will hereinafter appear, so 90 that when folded not in use the sections 6 are nested into two groups, designated generally as A and B in Figures 1 and 7, which groups are spread or divided along the line indicated at C in Figures 1, 3, 4 and 7. 95

In the construction of the umbrella, I employ a plurality of substantially rectangular sheets of material best shown in Figures 5 and 6. In Figure 5 the rectangular sheet is shown at 11, this sheet being creased along 100

its longitudinal axis, as at 12, so as to permit of folding along this axis to form the two portions 13, 13 and 14, 14 which, when the umbrella is spread, correspond each to one of the spans or sections 6 as shown in Figure 1.

The sheet 11 is provided with diagonal scorings 15, 15, 16, 16 which cross each other at the longitudinal axis 12, as indicated at 17 in Figures 5 and 6. This is the approximate 10 theoretical center of the umbrella, both when in the form shown in Figure 6 and in the form shown in Figure 1, as it is about this point that all of the sections converge or expand or unfold.

15 The scorings 15 and 16' define a substantially triangular area on the sheet designated 18, and, similarly, the scorings 16 and 15' define a substantially triangular area 19. When the sheet is thus scored or otherwise 20 marked so as to be susceptible of folding along the lines indicated, a plurality of other sheets are similarly formed. I have found that in an umbrella of dimensions of approximately 34 inches diameter, eleven sheets of material 25 will suffice to provide a complete circular top with an adequate number of reinforcing ribs to render the article satisfactorily serviceable.

These sheets may be then placed in superposed relationship and all uniformly cut with 30 the recesses indicated at 21, 21 in Figures 5 and 6 by removing a portion of the material in the areas 18 and 19 along the lines 22, 22 and 23, 23. After this has been done, a coating of a suitable adhesive is applied to the 35 remaining areas indicated at 24, 24 and 25, 25 and 26, 26, these being shaded in Figure 6 to indicate the adhesively coated portions. After thus being coated, the sheets are placed one upon the other in registration so that their 40 contiguous adhesively coated portions 24, 25 and 26 will be firmly connected. Such assembly is shown in Figure 6 wherein two of the sheets are shown. The sheet shown on the bottom of Figure 6, and for convenience 45 designated 27, is the bottom sheet of the stack and will, therefore, be the sheet appearing at the top of Figure 7 and designated 27, this sheet extending uninterruptedly along the bottom of the stack. The intervening sheets, 50 one of which is designated for convenience in Figure 6 as 28, are folded upon themselves along their longitudinal axes, that is, along the line 12 as shown in Figures 5, 6 and 7. The folded sections are placed in reverse 55 order, as will appear from Figure 7, with their respective longitudinal axes upon which they have been folded in abutting relation as shown at 29 in Figure 7. When the required number of sheets have been stacked and ad- 60 hesively connected, the complete stack is bent upon itself along the dotted line indicated at 30 in Figures 5 and 6 so that the adhesively coated portions 24 and 25 of each of the uppermost folded sections and the contiguous 65 halves of the adhesively coated portions 26 of

said sections will be joined by folding the complete stack on itself as shown in Figure 7. That is, assuming that there are five folded sections, such as 28, arranged on each side of the longitudinal axis of the bottom member 27 and the bottom member itself forming the eleventh section, it will be seen that when the five sections on each side of the axis 12 are adhesively connected the complete two groups may thus be folded on the line 30 and thereby adhesively connect their respective adhesively coated portions 24 and 25 as described above. It will be seen from Figure 4 that the two groups A and B which are, of course, the combined half sections folded as described, are connected finally as at D and E in Figure 4 so that there are ten intervening foldable sections 6 between the two folded parts of the member 27 which itself forms two additional sections which, upon inspection of Figure 1, will be seen to be substantially diametrically opposite each other when the umbrella is spread or extended for use. The adhesively connected portions 24, 25 and 26 form reinforcing ribs 7 when assembled and as they are of multiple ply material they possess considerable strength and rigidity.

Upon an inspection of Figure 2 it will be observed that by recessing the edges of the sheets employed in forming this article the reinforcing ribs have portions 7^a thereof which are substantially parallel to their top margins 8^a from the middle portion of the section to the outer edge and that reinforcing webs 8^b afforded by adhesively coated portions 26 are provided adjacent to the center of the umbrella. These recesses thus provided afford head room under the umbrella which is an advantage in some respects over the form shown in my co-pending application referred to.

When spread, the two sections A and B are bent along the line indicated at 17 or C by spreading the two sections A and B apart, as shown in Figures 3 and 4, so as to bring the edges F and G of the two groups A and B into abutment. In order to maintain the umbrella extended, I provide the handles 9 and 10 which latter are pivoted, as at 9^a and 10^a, respectively, at the middle portions of the two groups A and B between adjacent ribs 7.

In Figure 9 it will be observed that I reinforce this pivot joint by the provision of a separate U-shaped strip 35 of flexible material which is adhesively connected at 36 and 37 to said adjacent ribs. A fastening pivot pin 38 passes through the two portions of the strip 35 and through the adjacent portion of the handle but preferably not through the reinforcing rib itself. It is in some respects undesirable to pass the pin through the rib itself as it tends to weaken the rib and furthermore, in the use of the umbrella the pin rubs on the next adjacent rib 120

and may cause a weakening of the same. The contour of the handle is such, as indicated at 9^b and 10^b in Figure 2, that these handles overlap and thus may be grasped readily in one hand and tend to hold the umbrella in extended position.

I desire to emphasize the fact that the dimensions of each of the sections 6 is such that these sections have a curved slope upwardly, as indicated at Figure 8 when extended, so that this lends to the appearance of the umbrella and also prevents placing any appreciable stretching strain on the outer portions of these sections where they are most likely to be subjected to wind pressure in use. It will be understood, or course, that the material from which the umbrella is formed may be of a waterproof nature and that the adhesive employed may be any of the waterproof type now readily obtainable in the open market.

Having thus described my invention and illustrated its use, what I claim as new and desire to secure by Letters Patent is:

25 1. An umbrella including a top body portion formed of a plurality of flexible sections interconnected by contiguous integral flanges disposed at substantially right angles to the top when spread, said flanges having portions 30 of their outer edges substantially parallel to the top portion and other portions angularly related thereto.

2. An umbrella including a top body portion formed of a plurality of flexible sections 35 having marginal contiguous flanges connected to form multiple ply reinforcing members and lying at right angles to the plane of the top, a portion of each of said reinforcing members being recessed to give them a 40 tapering form toward the top adjacent the medial portion thereof.

3. A blank forming a section of a folding umbrella including a substantially rectangular flexible sheet having notched margins, 45 said sheet being folded upon itself along its longitudinal axis and being provided with gummed areas adjacent to said notched margins.

4. A blank forming a section of a folding 50 umbrella including a substantially rectangular flexible sheet having notched margins, said sheet being folded upon itself along its longitudinal axis and gummed areas adjacent the margins of said sheet, said areas 55 being relatively narrow strips of adhesive toward the ends of the sheet and at the medial portion extending from the margins thereof to said longitudinal fold, said sheet being foldable along the inner margins of said 60 gummed areas.

5. An umbrella including a top body portion and integral radial reinforcing portions constructed of a plurality of substantially plane pieces of material, the outer edges of 65 reinforcing portions being tapered from the

center of the top to their medial portions and parallel with the top from their medial portions to the outer ends thereof.

In testimony whereof I have hereunto signed my name.
